Attorney,

UNITED STATES PATENT OFFICE.

JAMES Y. FIELDS, OF DURHAM, NORTH CAROLINA, ASSIGNOR OF ONE-HALF TO
THOMAS Y. MILBURN, OF DURHAM, NORTH CAROLINA.

LAPPING MACHINE.

1,418,552.

Specification of Letters Patent. Patented June 6, 1922.

Application filed March 14, 1922. Serial No. 543,630.

To all whom it may concern:

Be it known that I, JAMES Y. FIELDS, a citizen of the United States of America, and resident of Durham, in the county of Durham and State of North Carolina, have invented certain new and useful Improvements in Lapping Machines, of which the following is a specification.

This invention relates to cotton treating machinery in its general application, and particularly to lapping machines in which the cotton is calendered, and has for an object the provision of means for shifting or shifting the drive of calender rolls to interrupt their motion, should conditions be abnormal as to the material passing through or between the rolls, or in case of absence of material, which latter might be occasioned by the breaking of the lap or lack of material in the hopper or feed to form a lap; the said invention being furthermore of utility to shift or ship the gearing or drive when the calender rolls are moved unduly, as might be the case when the lap passing between the rolls winds around either of the rolls, or when the lap is abnormally thick or unduly reduced in thickness.

It is a further object of this invention to produce a shifting or shifting mechanism which is mechanically operated and which constitutes an auxiliary to the usual manual controls that throw the gearing or drive into or out of operative positions; and in a more limited aspect, an object of this invention is to produce novel means, associated with a main side lever of machines of the character, effective to communicate the motion of the said lever when the said motion is abnormal, to the manually operated shifting element by which the elements of the drive are controlled.

With the foregoing and other objects in view, the invention consists in the details of construction, and in the arrangement and combination of parts to be hereinafter more fully set forth and claimed.

In describing the invention in detail, reference will be had to the accompanying drawings wherein like characters denote corresponding parts in the several views, and in which—

Figure 1 illustrates a side elevation of a fragment of a lapping machine with a device embodying the invention applied thereto;

Figure 2 illustrates a perspective view of the device disconnected from the machine; and

Figure 3 illustrates a sectional view on the line 3—3, omitting construction in front of the post.

In these drawings the side of the frame is shaped to form a guide 4 in which bearings 6 are supported to permit them to move, the said bearings constituting supports for the calender rolls 5. These parts are duplicated on opposite sides of the machine and as the calender rolls separate from or approach each other, their bearings are guided and held in operative relation to one another. The lowermost bearing for a calender roll is supported in a seat 100 formed in the frame. A yoke is provided and this yoke comprises the rods 7, a head plate 7^a and a base block 101. There are interposed filling blocks 7^b between the several bearings and between the uppermost bearing and the head, and therefore, as the bearings are forced apart, they serve to raise the head, and when they are allowed to approach each other, the head descends. As the rods 7 connect the head 7^a and the base block 101, it follows that the movement of the head is communicated to the base block. The base block is connected to the lever 8 by a pivot 8^a and as the base block goes up and down, the lever 8 is oscillated.

The starting lever 10 is moved or operated to shift the gearing of the drive for the calender rolls, and a latch 11 is oscillatable on a pivot 12 and it has a lug 13 which engages a lug 14 which may be positioned in any appropriate place to hold the said starting lever in position to retain the gearing in engagement during the operation of the calender rolls. When the latch is moved to cause a disengagement of the lugs 13 and 14, the starting lever automatically descends by gravity to effect disassociation of the driving gear in order that the calender rolls will come to rest. These elements are of conventional type and of well known arrangement, so that the details of construction by which the calender rolls are driven, or the means for shifting the gearing by the starting lever need not, it is thought, be further disclosed.

In order to communicate the motion of the lever 8 (imparted to it by the movement of the calender rolls) to the gear shifting mechanism as embodied in this disclosure of

the invention, the lever 8 is provided with a post 15, and this post may be applied to the lever in any appropriate way. It is here shown as having a clamp 16 which embraces the lever and is held in place by a set screw 17. This post has a reduced upper end 18, provided with a hook to which an apertured link 19 is applied, and hence as the lever 8 oscillates, it will serve to reciprocate the link 19. The link has a slot 20 near the end remote from the post, and this slot receives a pin 21 carried by the latch 11. The relation of parts is such that during the normal operation of the device the link will 15 slide on the pin without imparting motion to the lever, but upon abnormal upward movement of the weighted end of the lever 8, the end of the slot will encounter the pin 21 and impart movement to the link to dis- 20 engage the lugs 13 and 14 and permit the starting lever to drop and effect an uncoupling of the gearing.

The lever 8 has a flexible element 22 connected to it by a coupling 23, although the 25 manner of connecting the flexible member may be modified to suit particular requirements, and the said flexible element operates over an idle pulley 24 rotatable on a stud 25 which may be anchored to any part of the 30 frame of the machine, and the said flexible element is attached to an extension 26 of the latch 11 below its pivot, and should the outer end of the lever 8 descend abnormally, the flexible member will exert a pull 35 on the latch to cause a disengagement of the lugs 13 and 14, and this will likewise result in a release of the starting lever to effect a disengagement of the gearing.

The weight 27 on the outer end of the 40 lever serves to balance the lever when the calender rolls operate normally, but undue separation of the calender rolls or undue proximity of the peripheries of the calender rolls to each other will result in imparting 45 an abnormal movement to the lever and will result in tripping the latch in the manner stated.

It is to be remembered that the primary 50 object of this invention is to produce laps of uniform thicknesses, and that when variation occurs in the thicknesses of the laps beyond predetermined degrees, the operation of the calender rolls will be interrupted.

The frame is cut away as at 8^b to form a 55 clearance for the movement of the base block.

I claim:

1. In a lapping machine, calender rolls mounted for movement toward and away from each other, a lever oscillatably mounted 60 in proximity to the calender rolls, means for communicating the motion of the calender rolls as they approach or recede with relation to each other, to the lever, including means for starting and stopping the driving 65 mechanism, a starting lever for controlling

the last mentioned means, a latch for holding the starting lever while the driving mechanism is operating, a link having a slot near one end, a pin on the latch extending into the slot of the link, means for connecting the link to the first mentioned lever, a flexible element operating over a pulley and having one end connected to the first mentioned lever and the other end connected to the latch whereby a pull on the flexible member will oscillate the latch and release the starting lever. 70

2. In a lapping machine, calender rolls mounted for movement toward and away from each other, an oscillatably mounted 80 lever moved by the action of the rolls when separating from or approaching each other, a controlling lever for the driving mechanism of the rolls effective to start or stop the rolls, a latch for holding the starting lever in position to effect a rotation of the rolls, a link having a slot, a pin on the latch to receive the slot of the link, means for connecting the link to the first mentioned lever, whereby the link is reciprocated as the lever 90 oscillates, the arrangement being such that the link will impart motion to the latch upon abnormal movement of the lever in one direction, and means for imparting motion to the latch to disengage the starting lever 95 upon abnormal movement of the lever in the opposite direction.

3. In a lapping machine, calender rolls mounted for movement toward and away from each other, an oscillatably mounted 100 lever moved by the action of the rolls when separating from or approaching each other, a controlling lever for the driving mechanism of the rolls effective to start or stop the rolls, a latch for holding the starting 105 lever in position to effect a rotation of the rolls, a flexible element having one end connected to the lever, a pulley over which the flexible element operates, the said flexible member being connected to the latch whereby abnormal movement of the lever in one 110 direction oscillates the latch, and means for operating the latch upon abnormal movement of the lever in the opposite direction.

4. In a lapping machine having calender 115 rolls movable to approach and separate with relation to each other under the influence of the lap, a shifting mechanism for the calender roll drive, an oscillatably mounted lever, means for communicating the above 120 indicated motion of the calender rolls to the lever, means on one side of the lever's fulcrum for causing the shifting mechanism to disconnect the drive upon abnormal movement of the lever in one direction, and means 125 on the opposite side of the lever's fulcrum for causing the shifting mechanism to disconnect the drive upon abnormal movement of the lever in the opposite direction.

JAMES Y. FIELDS.
